UNITED STATES PATENT OFFICE.

HILMER N. ENHOLM, OF WINCHESTER, IDAHO.

GUMMED PAPER.

1,196,449.

Specification of Letters Patent. Patented Aug. 29, 1916.

Application filed May 19, 1915. Serial No. 29,166.

To all whom it may concern:

Be it known that I, HILMER N. ENHOLM, a citizen of the United States, residing at Winchester, in the county of Lewis and 5 State of Idaho, have invented certain new and useful Improvements in Gummed Paper, of which the following is a specification.

My present invention relates to new and 10 useful improvements in attaching devices, the primary object of my invention being the provision of an article which may be put up in convenient form and used in place of mucilage, glue, paste and other liquid or 15 semi-liquid adhesives.

More particularly my invention consists in the provision of an adhesive in the form of relatively thin paper both sides of which are glued or gummed, whereby a piece of 20 the double glued or gummed paper, of suitable size, may be inserted between two layers of paper or other articles to be fastened together, such articles, or the opposite sides of the glued paper having been previously 25 moistened.

My invention further contemplates the provision of alternate layers of paper unglued and paper glued upon both sides contained in a suitable cover, the sheets of glued 30 paper being creased, scored or perforated to divide them into stamps or seals of suitable size and shape for the purpose intended, each cover preferably containing a plurality of stamps or seals of different shapes and 35 sizes.

With these and other objects in view, my invention will be more fully described, illustrated in the accompanying drawing, and then specifically pointed out in the claim 40 which is attached to and forms a part of this application.

In the drawing: Figure 1 is a perspective view of one of my improved seal books, partially open; Fig. 2 is a plan view of one of 45 the glued sheets removed from the book, showing one manner of perforating such sheets; Fig. 3 is a similar view, showing the sheet perforated in another manner.

Corresponding and like parts are referred 50 to in the following description and indicated in all the views of the drawing by the same reference characters.

My present invention comprehends a container 10 in which are arranged alternate

layers of unglued paper 11 and glued paper 55 12. The unglued paper 11 is preferably oiled, waxed or otherwise treated in such a manner that the glued paper will not stick to it, even though moistened, and the glued paper, which is preferably relatively thin, 60 has both surfaces covered with a uniform coating of any suitable adhesive, such as glue or mucilage, a type of adhesive such as that employed upon postage and revenue stamps being preferred. 65

As will be clear from reference to Fig. 1 of the drawings, the glued and unglued sheets are identical in shape and size, such shape and size being both optional, and the container preferably consists of two correspondingly shaped pieces of cardboard or other suitable material 13 and 14 forming front and back covers between which the glued and unglued sheets are secured. These sheets may be secured in any suitable manner between the covers as by clenched staples 15 passed through the sheets and covers at one end in much the same manner in which stamp sheets are now secured in stamp packages. 80

The glued sheets may be creased or scored in various directions, as shown at 16, or formed with lines of perforations, as shown at 17, in order to provide seal or stamp portions 18 of various sizes and shapes. If the 85 container is a small one, certain of the sheets may be unscored and certain others scored to form seals of any preferred sizes and dimensions.

In use, a seal, of suitable size and dimensions, is severed from its containing sheet in the same manner that a stamp would be severed from a sheet of stamps and such seal is placed between the surfaces to be fastened together. The surfaces to be fastened together may be first moistened and the dry seal inserted between them or both sides of the seal may be moistened and placed between the dry surfaces. Again, one side of the seal or one of the surfaces 95 may be moistened and the seal applied and the other surface to be sealed or the other side of the seal then moistened. It will be apparent that seals of this nature are susceptible of wide and varied use. For instance, they may be employed in securing ungummed stamps to envelopes or in albums for sealing ungummed envelopes or for seal-

ing paper wrappings about parcels. In fact they may be put to practically any use for which glue, paste or mucilage is employed.

- 5 It will of course be understood that I do not wish in any way to limit myself to the specific type of cover or container for the glued sheets or to the size or shape either of the sheets themselves or of the seals out-
10 lined by the perforations formed in the sheets. Neither do I wish to be limited to the use of any particular adhesive upon the glued sheets or to the particular wax or other suitable coating for the unglued sheets.
15 Furthermore, material other than paper may be employed if found suitable or effi-
cient.

Having thus described the invention, what is claimed as new is:

A book of seals including covers and a 20 plurality of sheets of material all of the same shape and size bound between the covers, alternate sheets being oiled and the other sheets gummed, the gummed sheets being provided with weakened tearing lines 25 to divide the sheets, respectively, into seals of assorted shapes or sizes.

In testimony whereof I affix my signature in presence of two witnesses.

HILMER N. ENHOLM. [L. S.]
